DESIGN FOR A COMBINED SETTEE AND TELEPHONE CABINET

Frank P. Case, Chicago, Ill., assignor of one-half
to Henry A. Gosling, Chicago, Ill.

Application August 6, 1945, Serial No. 121,246

Term of patent 7 years

(Cl. D15—11)

To all whom it may concern:

Be it known that I, Frank P. Case, a citizen of the United States, residing at Chicago, in the county of Cook and State of Illinois, have invented a new, original, and ornamental Design for a Combined Settee and Telephone Cabinet, of which the following is a specification, reference being had to the accompanying drawing, forming a part thereof.

In the drawing:

Fig. 1 is a perspective view of a combined settee and telephone cabinet looking at the front thereof and showing my new design;

Fig. 2 is a perspective view thereof looking at the rear of the device; and

Fig. 3 is a front elevational view of the combined settee and telephone cabinet showing the seat thereof raised and showing the cover for the cabinet in open position.

I claim:

The ornamental design for a combined settee and telephone cabinet, as shown.

FRANK P. CASE.
